PORTRABLE DESK

Emmett J. Grainer, 1332 Biloxi Drive,
Cincinnati, Ohio 45231

Filed Aug. 8, 1968, Ser. No. 13,066

Term of patent 14 years

Int. Cl. D6—01

U.S. Cl. D33—7

FIGURE 1 is a view in perspective of my invention showing it in a position to be used as a writing platform;

I claim:

The ornamental design for a portable desk, as shown and described.
